UNITED STATES PATENT OFFICE.

JESSE J. HEAP, OF NYACK, NEW YORK, ASSIGNOR TO UNION SPECIAL MACHINE COMPANY, OF CHICAGO, ILLINOIS, A CORPORATION OF ILLINOIS.

SEWING MACHINE FOR FORMING CONCEALED STITCHES.

Application filed May 7, 1921. Serial No. 467,520.

To all whom it may concern:

Be it known that I, JESSE J. HEAP, a citizen of the United States, residing at Nyack, in the county of Rockland, State of New York, have invented certain new and useful Improvements in Sewing Machines for Forming Concealed Stitches, of which the following is a description, reference being had to the accompanying drawing and to the figures of reference marked thereon.

The invention relates to new and useful improvements in sewing machines for forming concealed stitches.

In the application filed by me September 15 24, 1919, Serial Number 325,827, there is shown, described and claimed a machine for forming concealed stitches wherein the needles pass through the respective inturned edges of the strip only, thus laying the 20 threads between the inturned edges and the body portion of the strip being stitched so that said stitches are concealed on the right or face side of the strip. In said application, the strip is led to the needles from a 25 point above the presser foot and in front of the needles, and then is fed toward the front of the machine. In the patent granted to J. F. Higgins No. 1,195,814, August 22, 1916, there is shown a similar machine for stitching strips to a body fabric and wherein the strip is led to the needles from a point in rear of the needles and is then fed toward the rear of the machine. In both of these 30 types of machines, the strip approaches the stitching point at an angle from one side of the needle path and is led away from the needle path on the same side thereof as it is fed to the needles. The direction of movement of the strip in the region where the 35 needles enter the strip is substantially parallel with the needle path and at right angles to the line of feed. Considerable difficulty has been experienced in the starting of short strips owing to the fact that the strip 40 when fed by hand into the machine can only be easily directed up to the point where the feed of the machine takes the strip, and the hand feed direction is substantially at right angles to the machine feed direction.

50 An object of the present invention is to provide devices for loading the strip, that is, for bending the end of the strip so that it may be taken by the feed and fed in the

proper direction to automatically draw the strip into the machine for stitching. 55

In the drawings:

Figure 1 is a front end elevation of a machine embodying my improvements;

Fig. 2 is a view partly in front elevation and partly in section from the front of the 60 machine;

Fig. 3 is a view of the structure shown in Fig. 2 on the line 3—3 thereof;

Fig. 4 is an enlarged view, partly in end elevation and partly in section through the 65 presser foot and the starting device for initially bending the strip and directing it to the feed dog;

Fig. 5 is a view of the supporting bracket and the feeding-in device from the rear of 70 the machine;

Fig. 6 is a sectional view on the line 6—6 of Fig. 4; and

Fig. 7 is a perspective view of the supporting bracket for the initial feeding of 75 the strip.

The invention as above noted is applied to a machine for forming concealed stitches, and particularly a machine for stitching short strips which have their edges inturned 80 and connected to form belt loops. The inturned edges are joined by stitches which pass through the inturned edges only and therefore the stitches do not show on the right or face side of the belt loop. These 85 belt loops are made from scrap material and are consequently made from short strips, and therefore, the operator is continually called upon to load the strips into the machine, that is, start the strips for stitching. 90 The strip passes through a guide which surrounds the needle paths in such a way that the edges of the strip are infolded and are directed across the path of the needle so that the needles enter and emerge from the same 95 face of the inturned edges. Thus it is that the strips as they are fed into the machine follow the general direction of the path of the needles, when they reach the region of stitching, and after they pass the region of 100 stitching, the strip is directed in a direction substantially at right angles to its path of movement while being stitched.

The invention consists particularly in a device which assists in the loading of the 105 strip, that is, the starting of the strip for the

stitching thereof. Said device consists of a 5 slidable plate which moves in a direction parallel with the under face of the presser foot and in a groove formed in the presser foot therefor. This device is spring pressed rearwardly or in a direction away from the needle path, and may be moved by the hand of the operator across the needle path and along the under side of the presser foot.

10 Thus the end of the strip may be folded or bent in the proper direction to be engaged by the feed so that the feed will automatically draw the strip through the guide and past the stitching point.

15 Referring more in detail to the drawings, my improvements are shown as applied to a sewing machine consisting of a supporting bed 1 carrying a bed plate 2 on which the material is held by the presser foot 3. The 20 presser foot 3 is carried by a presser bar 4 of the usual construction. Said presser foot is provided with a guide 5. The material is stitched by the stitching mechanism which includes, as shown in the drawings, two 25 needles 6 and 7, which are carried by a needle bar 8. Cooperating with the needles 6 and 7 beneath the work support is a looper 9. This looper cooperates with both needles, and therefore joins the needle thread loops, 30 thus forming connected rows of stitching. The guide 5 is shaped similar to the guide in my prior applications and operates to infold the edges of the strip being stitched. The strip is indicated in the drawings at S.

35 The passageway 10 of the guide 5 through which the strip passes extends in a direction substantially parallel with the needle paths. The strip is led from a position above the guide and in front of the needles through 40 this passageway 10. The edges are folded about the path of the needles so that the needles will enter the respective inturned edge portions of the strip and said inturned edge portions only. In other words, the 45 needles do not pass into the body portion of the strip and therefore, the stitches formed by the needles will be concealed on the right or face side of the strip. As the strip passes on down through the passageway 10, it ap-

50 proaches the plane of the work support, from a direction at right angles to the work support. The strip is then bent to the right as viewed in Figures 1 and 4 and is fed toward the front of the machine by the feed dog 11, which is the ordinary four-motion type. It will be seen that the operator may 55 readily by hand, force the end of the strip down through the passageway 10 until it reaches the work support. Then the strip 60 must be bent at a sharp angle in order to pass toward the front of the machine and to be engaged with the feed dog 11. This cannot be accomplished merely by pushing downwardly on the strip, and I have therefore 65 provided the following hand-operated

means for bending the end of the strip forwardly underneath the presser foot and into range of the feed dog 11. Said hand-operated means consists of a feeding-in plate 12 which is formed with teeth 13 on its forward 70 end. Said feeding-in plate 12 slides in a groove or cut-away portion 14 in the under side of the presser foot 3 (see Fig. 6). The feeding-in plate 12 is provided with an upwardly extending rib 15 which slides in a 75 recess in the bracket 16 formed integral with the sleeve 17 which is connected to an auxiliary member 18 attached to and moving up and down on the presser bar 4. The rib 15 is held in the recess in the bracket 16 by 80 means of two pins 19, 19 which extend through horizontal slots 20, 20 in the bracket 16. The rear end of the feeding-in plate is turned up as indicated at 21 to form a handle for the hand of the operator. Springs 22, 22 rigidly fixed to the sleeve 17 by means of 85 a screw 23 bear against the pins 19 and normally hold the feeding-in plate 12 retracted in the position shown in Figures 1, 4 and 7.

As above noted, the machine to which my 90 improvements are applied is particularly adapted for stitching belt loops made from scrap material, wherein the strips are comparatively short and the operator is continuously required to feed in new strips. In 95 order to start a strip, the presser foot is raised as shown for example in Fig. 4. The strip is led in through the passageway 10 until the end of the strip strikes the work support. Then the feeding-in plate 12 is 100 moved forward and the extreme forward end of this plate will engage the end of the strip projecting beneath the lower surface of the presser foot and bend the same forward. While the end is held bent forward by this 105 plate, the presser foot is lowered and the end of the strip will be caught by the feed dog 11 and the machine is then ready for the beginning of the stitching operation. The needles of course, are raised at this time. After the strip has been loaded into the 110 machine as above described, then the feeding-in plate is released, and the springs 22 will retract the same so that the stitching may proceed.

115 It is obvious that minor changes in the details of construction and the arrangement of the parts may be made without departing from the spirit of the invention as set forth in the appended claims.

120 Having thus described the invention, what I claim as new and desire to secure by Letters-Patent, is:—

1. The combination with a work support, 125 a presser foot, stitching mechanism including a needle, a feed dog, and means for guiding a strip from one side of the needle path into the needle path and thence away from the needle on the same side thereof as received; of loading means movable up and 130

- down with the presser foot and adapted to engage the end of the strip and bend the same in the direction of feed to cause the end of the strip to be engaged by the feed dog. 5
2. The combination with a work support, a presser foot, stitching mechanism including a needle, a feed dog, means for guiding a strip from above the presser foot and 10 from one side of the needle path into the needle path and thence away from the needle on the same side thereof as received, said strip passing from the guide underneath the presser foot, of a loading means 15 adapted to engage the end of the strip and bend the same underneath the presser foot and in a direction parallel with the under face of the presser foot whereby the end of the strip may be engaged by the feed 20 dog.
3. The combination with a work support, a feed dog, stitching mechanism including needles, a presser foot having an opening through which the needles and the strip to 25 be stitched pass, a guide for directing the strip through the opening in the presser foot and for infolding the edges of the strip and directing the same into the path of the needles, said presser foot having a recess 30 in its under face, a feeding-in plate adapted to be reciprocated in said recess and to engage the end of the strip projecting beneath the presser foot and bend said end into a direction parallel with the under surface of 35 the presser foot whereby the same is engaged by the feed dog.
4. The combination with a work support, a feed dog, stitching mechanism including needles, a presser foot having an opening 40 through which the needles and the strip to be stitched pass, a guide for directing the strip through the opening in the presser foot and for infolding the edges of the strip and directing the same into the path of the 45 needles, said presser foot having a recess in its under face, a feeding-in plate adapted to be reciprocated in said recess and to engage the end of the strip projecting beneath the presser foot and bend said end into a direction 50 parallel with the under surface of the presser foot whereby the same is engaged by the feed dog, and springs for retracting said feeding-in plate.
5. The combination with a work support, a feed dog, stitching mechanism including needles, a presser foot having an opening 55 through which the needles and the strip to be stitched pass, a guide for directing the strip through the opening in the presser foot and for infolding the edges of the strip and 60 directing the same into the path of the needles, said presser foot having a recess in its under face, a feeding-in plate adapted to be reciprocated in said recess and to engage 65 the end of the strip projecting beneath the presser foot and bend said end into a direction parallel with the under surface of the presser foot whereby the same is engaged by the feed dog, a bracket independent of the presser foot and movable therewith for supporting said feeding-in plate, and springs 70 for retracting said feeding-in plate.
6. The combination with a work support, a feed dog, stitching mechanism including needles, a presser foot having an opening 75 through which the needles and the strip to be stitched pass, a guide for directing the strip through the opening in the presser foot and for infolding the edges of the strip and directing the same into the path of the 80 needles, said presser foot having a recess in its under face, a feeding-in plate adapted to be reciprocated in said recess and to engage the end of the strip projecting beneath the presser foot and bend said end into a direction 85 parallel with the under surface of the presser foot whereby the same is engaged by the feed dog, a bracket independent of the presser foot and movable up and down therewith for supporting said feeding-in plate, said bracket having a recess in its under face, said plate having a rib extending into said recess, pins carried by said rib and movable in horizontal slots in the bracket 90 for supporting the rib in said bracket, said feeding-in plate having an upturned portion at the rear end thereof, and springs for engaging one of said pins for retracting the feeding-in plate. 95
7. The combination with a work support, a presser foot, stitching mechanism including two needles, and a looper cooperating with said needles and forming connected lines of stitching, a feed dog, and means for guiding the inturned edges of the strip from one side of the needle paths and said inturned edges into the needle paths and thence away from the needles on the same side thereof as received; of loading means adapted to engage the end of the strip and bend the same in the direction of feed to cause the end of the strip to be engaged by the feed dog. 100
8. The combination with a work support, a presser foot, stitch forming mechanism including a needle, a feed dog, and means for guiding the strip from one side of the needle path into the needle path and thence away from the needle, on the same side thereof as received; of loading means movable up and down with the presser foot and adapted to engage the end of the strip and bend the same in the direction of feed to cause the end of the strip to be engaged by the feed dog. 115
